INVENTOR.
George E. Warren

UNITED STATES PATENT OFFICE.

GEORGE E. WARREN, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE.

1,346,146.

Specification of Letters Patent. Patented July 13, 1920.

Application filed September 6, 1917. Serial No. 189,952.

To all whom it may concern:

Be it known that I, GEORGE E. WARREN, a citizen of the United States, residing at Swampscott, in the county of Essex and State 5 of Massachusetts, have invented certain Improvements in Shoes, of which the following description, in connection with the accompanying drawings, is a specification, like reference characters on the drawings indicating 10 like parts in the several figures.

This invention relates to the manufacture of shoes and particularly to improvements in shoe soles by means of which a sole can be maintained in place on a last bottom during 15 the operations of applying a shoe upper to the last and securing the upper to the sole. By way of illustration, the invention is herein shown as embodied in an insole of the type used in the manufacture of a welt 20 shoe but it is apparent that the invention is also applicable to the manufacture of shoes of other types.

It is the present practice in the manufacture of shoes of various types to tack the 25 insoles to the bottoms of the lasts and after the shoe uppers have been secured to the insoles to remove the insole fastening tacks. The tacks are necessarily located inside the 30 marginal area of the insole that is covered by the overlasted upper and, therefore, do not hold the edge of the insole closely to the edge of the last. In such subsequent operations on the shoe as the pulling-over operation, and sometimes the lasting operation, 35 this presents such a serious difficulty that special attachments are commonly provided on the machines which perform these operations to supplement the insole fastening tacks. Moreover the tacks are difficult to 40 remove and a tack is sometimes left, or its point is broken off, so that a part of the tack remains in the insole where it injures the foot of the wearer. Objects of the present invention are to provide an improved 45 sole the use of which will enable a more efficient attachment of the sole to the bottom of the last for the succeeding shoe upper shaping and securing operations than is practical with the tacks heretofore employed; to dispense with tacks or the like 50

fastenings such as those above named, thereby economizing in the labor cost incident to the use of tacks; and, furthermore, to eliminate the liability of injury from tacks or parts of tacks remaining in the finished shoe. 55

An important feature of this invention consists in a sole having means for holding its marginal edge to a last, such as a member or members adapted to extend beyond its periphery and be engaged with the last to 60 secure the insole in position on the last. In the illustrated embodiment of the invention an insole is provided with a plurality of adhesive coated members extended therefrom in position to attach to the sides of the last 65 and of suitable strength to hold the insole while the shoe upper is being applied and secured but to be broken readily by the operation of pulling the last from the shoe.

These and other features of the invention 70 will more fully appear from the following description read in connection with the accompanying drawings of an illustrative embodiment of the invention, and will then be particularly pointed out in the claims. 75

Figure 1 of the drawings is a perspective view of an insole illustrating a preferred embodiment of the invention.

Fig. 2 is a perspective view illustrating the use of the insole shown in Fig. 1. 80

In the drawings, 2 represents an insole of the type employed in the manufacture of welt shoes, and as shown it consists of a laminated structure having a sewing rib 4 formed upon its upper surface. In accordance with this invention, the insole is provided with means for securing it in position on the last 6 during the succeeding operations on the shoe. In the illustrated embodiment of the invention, these means comprise 85 a plurality of tabs 8 located at selected points about the periphery of the insole 2 and adapted to be attached to the sides of the last 6 to hold the insole against displacement on the last bottom and maintain its 90 edge against the edge of the last. The tabs 8 are preferably narrow strips of paper one end of each of which is secured between the laminated sheets comprising the insole with a portion projecting beyond the edge of the 100

insole and having its lower surface provided with an adhesive coating which enables the tab to adhere to the side of the last thereby holding the insole in proper position on the last. Preferably the tabs 8 are made of a paper which is of suitable strength to be readily torn when the operation of pulling the last from the shoe is performed so as to free the insole from the last. In order to hold the insole 2 upon the last 6 in the most advantageous manner, the tabs are located preferably at the toe, the tip line, the ball line and at either side of the breast line of the shoe, as illustrated. In commercial use of this invention, the insoles may conveniently be made in the ordinary manner with the tabs anchored between the two laminæ of the insoles as above described, the projecting portions of the tabs 8 being folded over on to the upper surface of the insoles as indicated in full lines in Fig. 1 of the drawings so that no inconvenience results in handling the insoles because of the pressure of the tabs.

In practice, the insole 2 is first placed in position upon the last 6 and the adhesive coating on the projecting portions of the tabs which are to be attached to the sides of the last treated to render the coating adhesive. The tabs 8 are then folded over against the sides of the last as illustrated in Fig. 2 of the drawings in which positions they become attached to the last. By reason of the described attachment of the insole to the last, the marginal edge of the insole is firmly held in position against the edge of the last whereby the pulling-over operation and the lasting operation may be performed upon the shoe without liability of the margin of the insole being raised out of position on the last bottom during these operations and the necessity of employing special attachments on the pulling-over and lasting machines to overcome this difficulty is eliminated. When the last is withdrawn from the shoe, the tab connections between the insole 2 and the last 6 are torn and the last readily withdrawn, the tabs 8 showing no indication in the interior of the shoe. It will thus be seen that the disadvantages are avoided which have been heretofore experienced with the use of the tacks for holding the insole in position on the last, for example, breaking the tacks in withdrawing them from the insole and the consequent liability of the tack remaining in the shoe and injuring the wearer's foot are eliminated and the defacement of the last by the numerous tack holes, and a better holding of the insole is obtained for the pulling-over and lasting operations.

Having fully described my invention, what I claim as new and desire to secure by Letters Patent of the United States, is:

1. As an article of manufacture, a sole having members adapted to extend beyond its periphery and be engaged with a last to secure the sole in position on the last. 65
2. As an article of manufacture, a sole having means for holding its marginal edge to a last. 70
3. As an article of manufacture, a sole having means for connecting its marginal edge at a plurality of points to a last. 75
4. As an article of manufacture, an insole having a plurality of members located at selected points on the periphery and adapted to be engaged with a face of a last to hold the insole in assembled relation to the last bottom. 80
5. As an article of manufacture, a sole having a plurality of flexible members adapted to be adhesively engaged with the side faces of the last to hold the sole in position on the last bottom during the operations of applying and securing the shoe upper. 85
6. As an article of manufacture, an insole having an adhesive coated paper strip extending into position to be stuck to the last and of suitable strength to hold the insole while the shoe upper is being applied and secured and to be broken by the operation of pulling the last from the shoe. 90
7. As an article of manufacture, a composite insole having a portion of an adhesive strip secured between the plies of the insole and another portion arranged to be attached to a last for holding the insole on the last bottom. 95
8. As an article of manufacture, an insole having a sewing rib and a feather and an adhesive coated member extending from the feather and adapted to be stuck to the last to hold the insole on the last bottom during the application of the upper and its connection to the sewing rib and to be broken by the withdrawal of the last from the shoe. 100
9. As an article of manufacture, an insole provided with a sewing rib and having a feather and means for connecting the said feather of the insole to a last. 105
10. As an article of manufacture, an insole having a sewing rib and a feather and a plurality of adhesive members arranged to hold the feather to the last at spaced points along the forepart and shank. 110

In testimony whereof I have signed my name to this specification.

GEORGE E. WARREN.
